United States Patent Office

Des. 189,181
Patented Nov. 8, 1960

189,181

BATHING CAP OR THE LIKE

Betty D. Geib, Roslyn Heights, N.Y., assignor to Betty Darling Enterprises, Inc., Nassau County, N.Y., a corporation of New York

Filed Apr. 27, 1959, Ser. No. 55,656

Term of patent 3½ years

(Cl. D3—13)

Fig. 1 is a side view of a bathing cap embodying my new design.

Fig. 2 is a rear view thereof, the front being plain and unornamented.

I claim:

The ornamental design for a bathing cap or the like, substantially as shown and described.
